COMBINED STEREOSCOPIC VIEWER AND SOUND REPRODUCER UNIT

Jerome L. Pinsler, 1012 Judson Ave., Evanston, Ill.
60202, and Lute P. Wassmann, 211 5th St., Wil-
mette, Ill. 60091

Filed June 30, 1969, Ser. No. 18,013

Term of patent 14 years

Int. Cl. D16—08

U.S. Cl. D61—1

Fig. 1

FIG. 2

FIG. 3

FIG. 1 is a perspective view of the combined stereoscopic viewer and sound reproducer unit showing our new design;

FIG. 2 is a front elevational view of the combined stereoscopic viewer and sound reproducer unit; and

FIG. 3 is a side elevational view, taken from the right in FIG. 2.

We claim:

The ornamental design for a combined stereoscopic viewer and sound reproducer unit, substantially as shown.
